ATTORNEY

UNITED STATES PATENT OFFICE.

GEORGE R. CONKLIN, OF MIAMI, FLORIDA, ASSIGNEE OF FIFTY-ONE PER CENT TO
MOMAN PRUIETT, ONE-FOURTH TO OEBAN C. PATTERSON, AND TWENTY-FOUR
PER CENT TO VERNON PRICE WILLIAMS, ALL OF MIAMI, FLORIDA.

ELECTRIC WATER HEATER.

Application filed July 25, 1924. Serial No. 728,163.

To all whom it may concern:

Be it known that I, GEORGE R. CONKLIN, a citizen of the United States, residing at Miami, in the county of Dade and State of Florida, have invented certain new and useful Improvements in Electric Water Heaters, of which the following is a specification.

This invention relates to water heaters and pertains particularly to the class of electric water heaters.

The primary object of this invention is the provision, in a manner as hereinafter set forth, of an electric water heater of improved construction, which is adapted to be placed in the water line to allow the water to pass therethrough and to heat the same during its passage through the heater.

A still further object of the invention is the provision, in a manner as hereinafter set forth, of an electric heater having an improved heating unit adapted to be easily and quickly removed from the device in a single unit without the necessity of disconnecting the device from the water line or otherwise disassembling the same.

A still further object of the invention is the provision, in a manner as hereinafter set forth, of an electric water heater having a controlling rheostat by means of which a large current can be turned on to quickly heat the water or the current can be cut down to a very low point to keep the water heated for any length of time desired.

A still further and final object of the invention is the provision, in a manner as hereinafter set forth, of an electric water heater of simple construction, easily and quickly disassembled for cleaning or replacement of parts, of neat appearance, efficient, and inexpensive to manufacture and install.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features of the invention as expressed in the appended claim.

In the drawings:

Figure 1 is a front elevation of the device embodying this invention.

Figure 2 is a longitudinal sectional view of the same.

Figure 3 is a transverse sectional view taken upon the line 3—3 of Figure 2, and

Figure 4 is a transverse sectional view taken upon the line 4—4 of Figure 2.

Referring now to the drawings in detail wherein like numerals of reference indicate corresponding parts throughout the several views, the device embodying this invention comprises a casing 1 of substantial length and here shown as circular in cross section, although this particular design is not essential and it is to be understood that the structure is not confined to this type of body. The body 1 is normally vertically positioned and has peripheral threads 2 at its lower end and is internally threaded as at 3 at its upper end. The lower end of the body 1 is closed by the bottom cap 4 which has the upstanding annular portion 5 interiorly threaded to engage the peripheral threads 2 of the body and the underside of the cap is drawn or tapered as at 6 to the interiorly threaded depending outlet nipple 7. Into this nipple one end of an inlet water pipe 8 is adapted to be threaded.

At the upper end of the body 1 there is located the head portion indicated as a whole by the numeral 9. This head 9 is of greater diameter than the body 1 as shown, and the lower portion thereof is drawn inwardly as at 10 to provide the constricted lower terminal portion 11 which is exteriorly threaded and adapted to engage in the interior threads 3 at the upper end of the casing 1 as shown. The upper portion of the head 9 is interiorly threaded as at 13 and further has formed about the upper edge thereof the annular flange or collar 14. Formed upon the body of the head 9 is a right angular extension 15 through which a threaded aperture is formed, and also through the body into the interior of the head, and into this threaded aperture one end of a water outlet pipe 16 is adapted to be threaded.

Fitted into the upper end of the head 9 is a heating unit support indicated as a whole by the numeral 17. This heating unit

support comprises a lower interiorly and exteriorly threaded sleeve 18 adapted to be threaded into the upper end of the head 9 engaging the threads 13 as shown in Figure 2, and the upper portion of this sleeve 18 has formed integral therewith an annular collar 19 which, as shown, is of greater diameter than the sleeve 18 and overhangs the outer side thereof to abut the top surface of the annular flange 14 of the head. The interior diameter of this collar 19 is also greater than the interior diameter of the sleeve 18.

Threaded into the sleeve 18 from the lower end thereof is a plug of insulation 20 which plug may be formed of hard rubber, bakelite, glass, porcelain or any other appropriate insulating material. The lower portion of the plug is of greater diameter than the body to form the annular rim 21 which when the plug is threaded into the sleeve 18 bears against and binds against the lower end of the sleeve and insulating washer 22. The upper end of the plug 20, when the same is threaded into the sleeve 18, is flush with the upper edge of the sleeve as shown.

Formed longitudinally through the plug 20 are three apertures through which certain conducting elements are adapted to extend. Positioned within the body 1 is a heating element, indicated as a whole by the numeral 23, consisting of a lower transverse or body portion 24 from which transverse body portion there extends three vertical electrodes 25, 26 and 27, respectively, the central electrode 26 being shorter than the two electrodes 25 and 27, as shown, and having threaded to the reduced portion 28 at the upper end thereof the conductor wire 29, the upper end of which is offset as at 30 and extended upwardly as at 31 through one of the passages through the plug 20. The upper end of this conductor wire is threaded to receive thereon a thumb nut 32. The electrodes 25 and 27 extend to the underside of the plug 20 and are then reduced to provide the reduced conducting elements 33 which extend through the other two apertures in the plug 20, and each of these conducting elements 33 has its upper end threaded in the manner similar to that of the conductor element 31 to receive thereon similar thumb nuts 34. The heating element 23 may be formed of some metal of high resistance which when current is forced

therethrough will become heated and thereby heat the water which surrounds it.

Secured to the inner side of the collar 19 is one leg of a bracket 35, the intermediate portion of which bracket is bent at right angles to the upper and lower portions to rest upon the top of the collar to more steadily hold the bracket in vertical position.

This bracket 35 supports at its upper end a rheostat 36 having a controlling knob 37 and a dial 38 upon its face showing the low, medium and high and off points of the rheostat. A lead-in electrical conductor 39 enters the back of the rheostat and after proper connection to the interior thereof the conductor wires 40 and lead therefrom for connection to the binding posts 31 and 33 of the heating element.

A top cap 41 is fitted over the collar 19 as shown in Figure 2, this cap having suitable apertures 42 therethrough for the passage of the conductor wires 40 and further having a cutout portion 43 therein to engage about the bracket 35 when in position. In this manner the thumb nuts and binding posts are well covered and protected by the cap against breakage or other damage and if preferred, this cap may be made of insulating material so that no danger of short circuiting will be had between the points 31 and 33 should the cap come in contact with these points.

From the foregoing description it may be seen that a novel and very efficient electric water heater has been provided which, due to its simple construction, may be easily disassembled, and the heating unit entirely removed from the water casing without disconnecting the casing from the water line.

Having thus described my invention what I claim is:

In a water heater of the character described, a relatively long casing having an inlet and an outlet through the sides thereof and closed at one end; an interiorly and exteriorly threaded collar threaded into the upper end of said casing, a plug of insulation threaded into said collar, a bare electrical resistance element depending from said plug into said casing for direct contact with a fluid therein, and means for conducting an electric current to said elements.

In testimony whereof, I affix my signature hereto.

GEORGE R. CONKLIN.
